UNITED STATES PATENT OFFICE.

WILBUR F. STEELE, OF STEELE, DAKOTA TERRITORY.

VAPOR-BURNER.

SPECIFICATION forming part of Letters Patent No. 402,996, dated May 7, 1889.

Application filed April 8, 1889. Serial No. 306,402. (No model.)

To all whom it may concern:

Be it known that I, WILBUR F. STEELE, a citizen of the United States, residing at Steele, in the county of Kidder and Territory 5 of Dakota, have invented certain new and useful Improvements in Vapor-Burners; and I do hereby declare the following to be a full, clear, and exact description of the invention, such as will enable others skilled in the art 10 to which it appertains to make and use the same.

My invention relates, generally, to vapor-burners for heating cars, rooms, and similar structures, and particularly to burners for vapor-stoves and other heaters of that class in which gasoline or other liquid hydrocarbon is used as the heating medium, said hydrocarbon being first heated, then vaporized, and the vapor then superheated before being consumed. It is a great desideratum in burners of this character to first secure uniform and thorough superheating of the vapor, so that the intensity of the heat produced will be greatly increased and the efficiency of the burner 20 promoted. Attempts have heretofore been made to produce apparatus or devices for accomplishing this result; but they have proven to be more or less defective and otherwise objectionable, owing to inherent defects in their 25 construction and to their costly and complicated character.

The objects of my invention are, first, to provide a burner of the class named which is simple in construction, cheap of production, 35 and efficient in operation, and one in which the vapor is superheated, so far as I am aware, much more thoroughly and uniformly than by the burners hitherto and now employed, and, second, to provide a burner of this class 40 in which the vapor is thoroughly and uniformly generated and superheated by agitation and deflection as it passes through its various parts, and at the same time is prevented from the formation of carbon.

My invention consists, first, in the combination, with the vaporizing-chamber of a vapor-burner, of a superheating-chamber, which is formed between the top of said vaporizing-chamber and an annular plate or disk located 50 within said chamber a short distance from its top, whereby the vapor from said vaporizing-chamber is caused to pass in a thin stratum between said disk or plate and the top of said chamber before being consumed, and thus be-

come highly and uniformly superheated, and, 55 second, in certain other novel and accessory features of construction and arrangement or combination of parts, which will be herein-after fully described, and pointed out in the claims.

In the accompanying drawing, forming part 60 of this specification, and in which the same reference-numerals refer to the same parts, the figure represents a central vertical section of a burner constructed in accordance 65 with my invention.

In said drawing, the reference-numeral 1 designates the supply-pipe, which leads from a receptacle containing gasoline or other liquid hydrocarbon, and is to be provided with 70 suitable cocks or valves (not shown) for regulating the supply of hydrocarbon to the receiving-chamber 2. The bottom of this chamber is concaved, as shown, to form a receptacle for any impurities contained in the oil, 75 and may be connected with said supply-pipe by a screw-joint or other suitable means. Rising centrally from this chamber is the feed-pipe 3, which leads to the vaporizing-chamber 4. This feed-pipe and vaporizing-chamber may be made integral with each 80 other or separate and connected by screw-threads or other suitable means. This vaporizing-chamber has the form of an inverted truncated cone. In other words, it is provided with an outwardly-flared wall or bottom, 5, and with an annular flanged flat top or cover, 6, as shown.

7 designates the burner-nipple, and 8 the needle-hole through which the vapor escapes 90 after being thoroughly superheated. This burner-nipple is placed centrally of and in communication with the superheating-chamber, herein-after described. Suitably supported within the vaporizing-chamber near 95 its top is an annular plate or disk, 9, which has a diameter slightly less than the interior diameter of said chamber, whereby a small space is left between its periphery and the upper portion of said chamber. This annular plate or disk is placed immediately below or close to the top or cover 6 of the vaporizing-chamber 4, so as to leave a small space between its top surface and the under surface 100 of said top or cover, and thus constitute the 105 superheating-chamber 10.

A deflector, 11, for deflecting the heat down upon the superheating-chamber, consists of a

plate, 12, having the form of an inverted cone, and provided with legs 13, which rest upon the top or cover 6 of the vaporizing-chamber. This plate or deflector is also provided with a lug, 14, which is formed with an opening, 15, in which may be inserted a suitable instrument for removing said deflector for the purpose of cleaning the same or to permit access to the parts beneath. An oil cup or receptacle, 16, for heating the receiving and vaporizing chambers previous to lighting the burner, is arranged intermediate of said chambers. The top of the receiving-chamber forms a bottom, 16', for this oil cup or receptacle, while its wall or periphery is formed by an upward extension or flange, 17, of the casing of said receiving-chamber; or it may be formed of a separate flange secured to and projecting upwardly from said bottom and casing.

The operation of my improved vapor-burner will be readily understood from the foregoing in connection with the following description. A suitable quantity of liquid hydrocarbon is first introduced into the receiving-chamber through the supply-pipe 1; then the oil previously placed in the receptacle or oil cup 16 is lighted, which heats both the vaporizing and receiving chambers, and causes the liquid contained in the latter to be highly heated, and give off more or less vapor, which, together with the oil, then passes from said receiving-chamber through the feed-pipe 3 into the vaporizing-chamber, where it is met by the annular retarding and deflecting disk 9, and caused to escape between the periphery thereof and the upper portion of the vaporizing-chamber into the narrow space which constitutes the superheating-chamber 10; thence it passes in a thin stratum through the burner-nipple 7, and out at the needle-hole 8, where it is ignited. The flame from the nipple, owing to the inverted conical shape of the deflector or plate 12, is deflected downwardly and outwardly, and the heat thereof causes the superheating-chamber to become highly heated, thus causing a thorough and uniform superheating of the vapor as it passes into and out of the superheating-chamber 10, and at the same time preventing the formation of carbon.

Having thus described my invention, what I claim is—

1. In a vapor-burner, the combination, with a vaporizing-chamber, of a retarding and deflecting disk located therein, and a superheating-chamber formed between and by said disk and the top of said vaporizing-chamber, substantially as and for the purpose described.

2. In a vapor-burner, the combination, with a vaporizing-chamber provided with a top or cover having a burner-nipple, of a retarding and deflecting disk located within said chamber and at a short distance below said top or cover, substantially as and for the purpose described.

3. In a vapor-burner, the combination, with

the vaporizing-chamber 4, provided with the top or cover 6, having the burner-nipple 7, of the retarding and deflecting disk 9, arranged just beneath said top or cover and forming therewith the superheating-chamber 10, and the deflector-plate 12, for deflecting the heat down upon said superheating-chamber, substantially as and for the purpose described. 75

4. In a vapor-burner, the combination of the receiving-chamber 2, the feed-pipe 3, the vaporizing-chamber 4, the retarding and deflecting disk 9, located therein, and the burner-nipple 7, substantially as and for the purpose 80 described.

5. In a vapor-burner, the combination of the supply-pipe 1, the receiving-chamber 2, having a concaved bottom, the feed-pipe 3, the vaporizing-chamber 4, the disk 9, the burner-nipple 7, and the deflector-plate 12, substantially 85 as and for the purpose described.

6. In a vapor-burner, the combination, with the receiving-chamber 2, the feed-pipe 3, and the vaporizing-chamber 4, having an outwardly-flaring wall or bottom, 5, a flat top, 6, and a central burner-nipple, 7, and the retarding and deflecting disk 9, substantially as and for the purpose described. 90

7. In a vapor-burner, the combination of the receiving-chamber 2, the oil-cup 16, the feed-pipe 3, the vaporizing-chamber 4, the retarding and deflecting disk 9 located therein, the burner-nipple 7, and the deflector-plate 12, substantially as and for the purpose described. 95

8. In a vapor-burner, the combination, with the vaporizing-chamber 4, the retarding and deflecting disk 9 located therein, and the burner-nipple 7 in the top of said chamber, 100 of the deflector 11, consisting of the annular plate 12 and the legs 13, substantially as described.

9. In a vapor-burner, the combination of the receiving-chamber 2, having a concaved bottom, the supply-pipe 1, fitted in the side of said chamber, the feed-pipe 3, the oil-cup 16, the vaporizing-chamber 4, having an outwardly-flaring wall or bottom, 5, a flat top, 6, and a central burner-nipple, 7, the retarding 115 and deflecting disk 9, and the deflector 11, substantially as described.

10. In a vapor-burner, the combination of the receiving-chamber 2, having a concaved bottom, the supply-pipe 1, fitted in the side 120 of said chamber, the feed-pipe 3, the oil-cup 16, the vaporizing-chamber 4, having an outwardly-flaring wall or bottom, 5, a flat top, 6, and a central burner-nipple, 7, the retarding and deflecting disk 9, and the deflector 11, 125 consisting of the plate 12, having the shape of an inverted cone, and the legs 13, substantially as described.

In testimony whereof I affix my signature in presence of two witnesses.

WILBUR F. STEELE.
